UNITED STATES PATENT OFFICE.

ALEXIS C. HOUGHTON, OF SYRACUSE, NEW YORK.

BENZOYL SUCCINYL PEROXID AND PROCESS OF MAKING SAME.

No. 821,291.

Specification of Letters Patent.

Patented May 22, 1906.

Application filed September 25, 1905. Serial No. 280,080. (Specimens.)

To all whom it may concern:

Be it known that I, ALEXIS C. HOUGHTON, a citizen of the United States, residing at Syracuse, in the county of Onondaga, State of New York, have invented certain new and useful Improvements in Antiseptic Compounds; and I do declare the following to be a full, clear, and exact description of the invention, such as will enable others skilled in the art to which it appertains to make and use the same.

This invention relates to an antiseptic compound consisting of a monobasic peroxid derived from benzoic peracid and the anhydrid of succinic acid.

The compound has the following formula:

and I have named it "benzoyl succinyl peroxid."

This compound has the following distinguishing features: It is a colorless, crystalline body, very soluble in acetone, soluble in acetic ether, chloroform, and alcohol, moderately soluble in benzene and ethyl ether, slightly soluble in acetic acid, insoluble in ligroin. It has a melting point of about 96° centigrade. It possesses an aromatic odor, a sharp peppery taste, and is an intense germicide.

In water the compound is decomposed, 40 forming succinic acid and benzoic peracid.

The process of forming benzoyl succinyl peroxid consists in adding to one hundred cubic centimeters of a ten-per-cent. watery solution of benzoic peracid five grams of succinic anhydrid. The benzoyl succinyl peroxid separates out as a fine colorless powder, which is removed by filtration from the watery mixture.

Having thus fully set forth my invention, 50 what I claim as new, and desire to secure by Letters Patent, is—

1. An antiseptic compound, consisting of a monobasic peroxid derived from benzoic peracid and the anhydrid of succinic acid, which 55 is characterized by the following properties: it is a colorless, crystalline body, possesses an aromatic odor and a sharp, peppery taste; in water it forms benzoic peracid and succinic acid, and it is an intense germicide. 60

2. An antiseptic compound, consisting of a monobasic peroxid derived from benzoic peracid and the anhydrid of succinic acid, which is characterized by the following properties: it is a colorless, crystalline body, possesses an 65 aromatic odor and a sharp, peppery taste; it is soluble in chloroform, alcohol and benzene; insoluble in ligroin, and has a melting-point of about 96° centigrade; when placed in water it gradually goes into solution with the 70 formation of benzoic peracid and succinic acid, and it is an intense germicide.

In testimony whereof I sign this specification in the presence of two witnesses.

ALEXIS C. HOUGHTON.

Witnesses:

E. S. WHEELER,
I. G. HOWLETT.

It is hereby certified that Letters Patent No. 821,291, granted May 22, 1906, upon the application of Alexis C. Houghton, of Syracuse, New York, the title of the invention was erroneously written and printed "Benzoyl Succinyl Peroxid and Processes of Making Same," whereas the said title should have been written and printed *Benzoyl Succinyl Peroxid*, and in line 28 the word "benzoyl" should be *benzoyl*; and that the said Letters Patent should be read with these corrections therein that the same may conform to the record of the case in the Patent Office.

Signed and sealed this 12th day of June, A. D., 1906.

[SEAL.]

. F. I. ALLEN,
Commissioner of Patents.
